CLAIM

The ornamental design for a battery cover with movable handle, as shown and described in FIGS. 1-26.

DESCRIPTION

FIG. 1 is a perspective view of the battery cover with movable handle showing a first embodiment of our new design;

FIG. 2 is a top plan view thereof;

FIG. 3 is a perspective view of the handle portion thereof, the cover portion being shown in broken lines for purposes of disclosure only;

FIG. 4 is a top plan view of the handle portion thereof, the cover portion being shown in broken lines for purposes of disclosure only;

FIG. 5 is a front elevational view thereof;

FIG. 6 is a rear elevational view thereof;

FIG. 7 is a right side elevational view thereof, the left side being a mirror image;

FIG. 8 is a bottom plan view thereof;

FIG. 9 is a perspective view thereof with the handle shown in the "stored" position;

FIG. 10 is a perspective view of the battery cover with movable handle showing a second embodiment of our new design which utilizes a single vent, in all other respects it is identical to the embodiment of FIG. 1;

FIG. 11 is a top plan view thereof;

FIG. 12 is a perspective view of the battery cover with movable handle showing a third embodiment of our new design which does not utilize a visible vent, in all other respects it is identical to the embodiment of FIG. 1;

FIG. 13 is a top plan view thereof;

FIG. 14 is a perspective view of the battery cover with movable handle showing a fourth embodiment of our new design;

FIG. 15 is a top plan view thereof;

FIG. 16 is a perspective view of the handle portion thereof, the cover portion being shown in broken lines for purposes of disclosure only;

FIG. 17 is a top plan view of the handle portion thereof, the cover portion being shown in broken lines for purposes of disclosure only;

FIG. 18 is a front elevational view thereof;

FIG. 19 is a rear elevational view thereof;

FIG. 20 is a right side elevational view thereof, the left side being a mirror image;

FIG. 21 is a bottom plan view thereof;

FIG. 22 is a perspective view thereof with the handle shown in the "stored" position;

FIG. 23 is a perspective view of the battery cover with movable handle showing a fifth embodiment of our new design which utilizes a single vent, in all other respects it is identical to the embodiment of FIG. 14;

FIG. 24 is a top plan view thereof;

FIG. 25 is a perspective view of the battery cover with movable handle showing a sixth embodiment of our new design which does not utilize a visible vent, in all other respects it is identical to the embodiment of FIG. 14;

FIG. 26 is a top plan view thereof.

The broken line showing of the battery container in FIGS. 1, 2, 5-7, 9, 10, 12, 14, 18-20, 22, 23 and 25 is for illustrative purposes only and forms no part of the claimed design.
